UNITED STATES PATENT OFFICE.

JACOB M. MARCH, OF NARBERTH, PENNSYLVANIA.

WEATHER-STRIP.

SPECIFICATION forming part of Letters Patent No. 546,236, dated September 10, 1895.

Application filed May 31, 1895. Serial No. 551,137. (No model.)

To all whom it may concern:

Be it known that I, JACOB M. MARCH, a citizen of the United States, and a resident of Narberth, Montgomery county, Pennsylvania, have invented certain Improvements in Weather-Strips, of which the following is a specification.

The object of my invention is to so construct a weather-strip that it will fit tightly in the corner formed by the window and frame when the window is down, but as soon as the window is raised one part will move away from the other, so that the window can be raised without undue friction.

15 A further object of my invention is to secure the parts together that form the weather-strip in such a manner that the strip can be readily applied to the window by an unskilled mechanic and can be so folded that the strips 20 can be packed in a small compass.

In the accompanying drawings, Figure 1 is a perspective view of a short section of my improved weather-strip. Fig. 2 is a section on the line 2 2, Fig. 1. Fig. 3 is an end view 25 showing the sections folded for shipment. Fig. 4 is a perspective view illustrating the application of my invention to a window. Fig. 5 is a sectional view of a window-frame, showing the weather-strip attached, the window-30 sash being in the closed position. Fig. 6 is a view similar to Fig. 5, showing the sections of the weather-strip parted, the window-sash being raised. Fig. 7 is a view of the strip, 35 showing one section detached. Fig. 8 is a view of a modification of my invention.

A is the weather-strip, which is adapted to fit into the corners b at the junction of the sash B with the frame B', as clearly illustrated in Figs. 4 and 5.

40 The weather-strip is composed of three sections a a' a'', the section a being triangular in cross-section and tapered throughout its length, the distance from the point x to the back x' varying, as clearly indicated in Figs. 1 and 2. The edges y of the strips a' and a'', which bear against the back x' of the strip a, are beveled on the same line as the back x', while the width of the entire weather-strip 45 does not vary, the edges z z being always the same, so that when the weather-strip is attached to the window sash and frame its edges 50 are parallel with the lines of the window sash

and frame, the beveled portion not being exposed.

In order to hold the several strips together 55 during shipment or while on sale, I secure at intervals to the strips a band d, of fabric or other yielding material, which can be cut so as to separate one of the strips from the center strip a, as shown in Fig. 7, the other strip remaining attached to the center strip. If, for instance, the weather-strip is to be attached to a window, as shown in Fig. 5, the section a' is separated from the section a, and the section a'', with the section a attached, is secured 60 to the window-frame B' by brads or screws, the section a fitting snugly into the corner formed by the window sash and frame, but not forced into the corner to such an extent as to prevent the easy working of the sash. 65 The strip a is so arranged that its wide end is at the bottom of the window-frame. The strip a' is adjusted in position and forced 70 tightly against the strip a, so as to make a tight fit, and is then secured to the window-75 sash by brads, screws, or other fastenings, as shown in Fig. 5. So it will be seen that when the sash is down, as indicated in said figure, the weather-strip excludes the air, making a 80 tight fit at the corner; but as soon as the sash is raised the section a' will be drawn away from the section a, as shown in Fig. 6, so that the window-sash can be raised without undue friction.

It will be seen that by simply turning the 85 weather-strip around and detaching the section a' from the section a the strip will fit properly on the opposite side of the window, the strip a'' being secured to the sash and the strip a' being secured to the frame. 90

In some instances the band d may extend the full length of the strip, and, when necessary, the back x' of the strip a may be covered with felt, or the entire strip a may be incased in felt or other suitable material. 95

In some instances the corner piece may form part of one of the side strips, as shown in Fig. 8, there being sufficient yield in the strip to enable the other side strip to force the corner piece into the corner when the 100 window-sash is down.

I claim as my invention—

1. The combination in a weather strip, of the triangular corner section adapted to fit in

the corner of the window and having a tapered back, with a bearing strip adapted to rest against the back of the corner strip and to force it into the corner when the window is closed, substantially as described.

2. The combination of a weather strip made of three sections, the angular corner section adapted to the corner of the window and tapered at the back, with side strips adapted to rest against the back of the corner strip, one side strip and the corner strip being secured to the frame or sash and the other side strip being secured to the other part, substantially as described.

3. The combination of the triangular corner strip having a tapered back and side strips

adapted to the back, one side strip being movable independent of the corner strip, substantially as described.

4. The combination of the three strips, the central strip having the tapered back against which the side strips rest, with tapes binding the said strips together, substantially as described.

In testimony whereof I have signed my name to this specification in the presence of two subscribing witnesses.

JACOB M. MARCH.
